(57) CLAIM

The ornamental design for a vehicle taillight, as shown and described.

DESCRIPTION

FIG. 1 is a front top left side perspective view for a vehicle taillight, showing my new design;

FIG. 2 is a front elevational view of FIG. 1 thereof;

FIG. 3 is a rear elevational view of FIG. 1 thereof;

FIG. 4 is a left side elevational view of FIG. 1 thereof;

FIG. 5 is a right side elevational view of FIG. 1 thereof;

FIG. 6 is a top perspective view of FIG. 1 thereof; and,

FIG. 7 is a bottom perspective view of FIG. 1 thereof.

The broken lines indicate unclaimed portions of the design and form no part of the claimed design.
